UNITED STATES PATENT OFFICE

149,999

DESIGN FOR A SPECTACLE FRAME

Aaron Coen, Newark, N. J.

Application January 10, 1947, Serial No. 136,031

Term of patent 3½ years

(Cl. D57—1)

To all whom it may concern:

Be it known that I, Aaron Coen, a citizen of the United States, residing at Newark, New Jersey, have invented a new, original, and ornamental Design for Spectacle Frames, of which the following is a specification, reference being had to the accompanying drawing, forming part thereof, in which

Figure 1 is a side elevational view of a spectacle frame showing my new design, the opposite side presenting substantially the same appearance as the side shown; and

Figure 2 is a top plan view thereof.
I claim:

The ornamental design for a spectacle frame as shown and described.

AARON COEN.
